16 Claims. (Cl. 272—38)

1

This invention relates to amusement apparatus and more particularly to toy Ferris wheels.

The prior art Ferris wheels are more or less completely concerned with full scale amusement park apparatus. The construction of these wheels is not well adapted either from the standpoint of efficiency or of economy for reproduction in small scale apparatus such as toys.

Having in mind the defects of the prior art apparatus, it is an objective of this invention to provide a small scale Ferris wheel device, for use as a toy, that is simple and economical in construction and operation while being interesting to control and attractive to watch when in operation. It is contemplated that a structure comprising two wheels mounted on the ends of a rotating boom may comprise a single drive for rotating each of the wheels and the boom along with control means for adapting the drive to rotate either of the wheels or the boom separately or in any desired combination. It is desirable to enhance the appearance of the apparatus, particularly when it is in operation, by means of illumination associated with the moving parts of the apparatus and to provide a simple and economical but efficient electric supply for the means of illumination, including a unique arrangement for transferring current from one to the other of relatively movable parts.

The foregoing objects and others ancillary thereto are preferably accomplished, according to a preferred embodiment of the invention, by disposing two wheels on the ends of a boom which is pivotally mounted, centrally thereof, on a stationary upright standard, and selectively driving each of the wheels or the boom separately or in combination from a single drive means. Specifically, two wheels of the usual Ferris wheel type are pivotally mounted on the bifurcated ends of a boom and have beveled gears fixed on their shafts. The boom is pivotally mounted at its center on a shaft supported by the upper ends of a bifurcated tower. A bevel gear is fixed on the boom shaft, and two double bevel gears are supported by anti-friction bearings, mounted on the shaft which permit free rotation of the double bevels relative to the boom shaft. Two shafts are mounted longitudinally of the boom having small bevels fixed on their ends and in mesh respectively with bevel gears fixed on the wheel shafts and with one side of each of the double bevels. Three upright drive shafts have bevels on their upper ends in mesh respectively with the bevel on the boom shaft and the opposite sides of each of the double bevels from

2

that of the aforementioned shafts connecting the wheels with the double bevels. By this arrangement, each of the wheels or the boom may be separately rotated in accordance with the drive transmitted by the three vertical shafts.

Each of the three vertical shafts are driven by a single power shaft but are associated therewith in such a manner that any one of the three may be disconnected therefrom. This drive system may be accomplished by different arrangements, however, they may all incorporate the basic concept of employing solenoids for disconnecting the different drive gears. In one of these arrangements, the vertical boom drive shaft is provided with a worm gear meshing with a worm carried by the free elements of a clutch mounted on the power shaft. The free clutch element is resiliently urged into engagement with a driven element fixed on said power shaft and is adapted to be disengaged by a lever operable by an electromagnet, such as a solenoid. The upright wheel drive shafts are suspended in their upper bearings and have their lower ends journaled in levers that may be swung to engage or disengage worm gears on said shafts and worms on the power shaft. Solenoids are connected with said levers to swing the bottoms of the shafts to disengage their worm gears from said worms. In the other arrangement, all three of the upright shafts are swingably mounted and bevel gears are employed rather than worms and worm gears. This latter construction permits the upright shafts to be mounted in a line directly above the horizontal drive shaft.

It would appear that the wheels and the boom would cease rotation when their respective drive shafts were disengaged from the power shaft. Such is not the case, however, particularly with heavier constructions, due to the fact that momentum causes continued rotation for some time and, in addition, if at least one of the shafts is retained in driving engagement, frictional forces also tend to continue rotation of members which have been disengaged from their respective drive. As long as part of the apparatus is being driven, momentum and friction tend, to a degree, to continue rotation of other parts of the apparatus. Accordingly, it is desirable with heavier constructions, to provide breaking means for stopping rotation of the wheels or the boom upon disengagement of their respective drive shafts from the power shaft. The braking means are most conveniently and simply arranged to cooperate with the lower ends of the drive shafts. In the

lighter construction, the brake means may be provided for the boom only.

For the wheel shafts the brake may be in the form of a fixed tooth or stop that is positioned so as to be engaged by the worm gear when it is swung out of engagement with the worm, and thus be held against further rotation. Due to the weight and momentum of the boom, however, a friction type of brake is preferred so as to prevent sudden stops that might be harmful to the apparatus. To accomplish this, a pair of friction blocks are positioned astride the upright boom shaft and are retained in constant frictional engagement therewith so that the shaft is actually driven in opposition to this braking action. Consequently, when the clutch is disengaged the boom shaft will not come to a sudden stop, but will slow down gradually. In order to eliminate sudden starts, which are just as undesirable as sudden stops, the boom drive shaft has its worm gear freely mounted thereon and connected therewith by means of a "free wheeling" one-way clutch in the form of a helical spring wrapped around the vertical shaft and having an end fixed to the gear.

In order to enhance the appearance of the apparatus, small electric lights may be mounted on the revolving parts, particularly the wheels. In view of the fact that a harmless 12-volt current is used, these lights may be grounded to the apparatus, thereby requiring but a single line running to the lights. In order to transfer current between the relatively movable parts, a spring contact is mounted on the supporting part to bear against a button contact mounted on the end of the shaft carrying the rotating part, thereby permitting the transfer of electric current while the two contacts are rotating or pivoting relative to each other. This structure supplants the relatively expensive and complicated brush and collecting ring arrangement usually employed for transferring current between relatively rotatable members.

The novel features that are considered characteristic of the invention are set forth with particularity in the appended claims. The invention itself, however, both as to its organization and its method of operation, together with additional objects and advantages thereof, will best be understood from the following description of specific embodiments when read in connection with the accompanying drawings, wherein like reference characters indicate like parts throughout and in which:

Fig. 1 is a partial side view in elevation of the upper portions of a dual Ferris wheel including a rotatable boom supporting the wheels;

Fig. 2 is an end view in elevation of the apparatus shown in Fig. 1;

Fig. 3 is a detail view of the base of the apparatus and the power drive means;

Fig. 4 is a side view in elevation of one of the wheel shafts;

Fig. 5 is a fragmentary view in cross section through the drive end of one of the wheel shafts;

Fig. 6 is an enlarged fragmentary side view in elevation of a boom shaft;

Fig. 7 is a cross section view taken on line 7—7 of Fig. 6;

Fig. 8 is a cross sectional view taken through a portion of one end of the boom shaft;

Fig. 9 is a fragmentary view partially in elevation and partially in cross section of the power shaft and clutch mechanism for driving the boom;

Fig. 10 is a fragmentary view in elevation of the boom drive shaft and its associated worm gear with the one-way clutch therebetween;

Fig. 11 is a fragmentary view in cross section through the end of one of the wheel shafts and showing the current transfer means;

Fig. 12 is a top plan view of a modification of the power drive means;

Fig. 13 is a side view in elevation of the drive means shown in Fig. 12;

Fig. 14 is a side view in elevation of a single Ferris wheel;

Fig. 15 is a cross sectional view taken on line 15—15 of Fig. 14; and

Fig. 16 is a detail view in elevation of the drive mechanism for the single Ferris wheel.

A Ferris wheel to overcome the defects hereinbefore enumerated should have the totally distinct characteristics of comprising a single power source for selectively driving one or more of a plurality of rotatable elements. Accordingly, a preferred embodiment of the invention, referring to Fig. 1 of the drawings, is constituted by an apparatus composed of a pair of wheels 15 respectively mounted on shafts 16 which are respectively journaled in bearing members 17 supported by the opposite ends of a boom 18 that is fixed on a shaft 19 journaled in bearing members 20 supported by the upper ends of a bifurcated tower 21. The wheels 15 are of the usual Ferris wheel type and pivotally support a plurality of passenger carriers 22. As both of the wheel structures and apparatus associated therewith are identical, no differentiation is made in describing them and the same reference characters are applied to both.

It is desired to rotate each of the wheels 15 about their pivots in the ends of the boom 18 and also to rotate the boom on its central supporting shaft 19. In order to accomplish the desired rotation, as best shown in Figs. 5 and 6, bevel gears 25 are fixed on the wheel shafts 16 and are in mesh with bevel pinions 26 mounted on the outer ends of drive shafts 27 which are carried radially by the boom 18. As more clearly shown in Figs. 6, 7 and 8, the radial shafts 27 have beveled pinions 28 mounted on their inner ends which are in mesh with one bevel of double bevel gears 29 which are supported by the boom shaft 19. The other bevels of the gears 29 are driven by bevel pinions 30 mounted on the upper ends of upright drive shafts 31. The boom 18 is rotated by means of a relatively large bevel gear 35 fixed on its shaft 19 and in mesh with a bevel pinion 36 mounted on the upper end of an upright drive shaft 37.

The overall arrangement of the drive is best shown in Fig. 2 wherein the boom 18 is shown in a vertical position so that one of the wheels 15 is in its lower, or, passenger loading and unloading position. The tower 21 is composed of two spaced sections mounted on a base member 40 and having bearing portions 20 at their upper ends in which are journaled the opposite ends of the boom shafts 19. The boom 18 is composed of two axially spaced elements having bearing members 17 at their outer ends for journaling the wheel shafts 16 adjacent their ends. The wheels 15 are fixed on their shafts 16 between the spaced boom elements and may be spaced from the bearing members 17 by collars 23. The bevel gears 25 are fixed on one of the ends of each of the wheel shafts 16, being spaced from the adjacent bearing member 17 by another collar 23. In order to accommodate the separate wheel

drives, the bevel gears 25 are on the respective opposite ends of their shafts 16 so as to be positioned on opposite sides of the boom 18. The radial shafts 27 are mounted on opposite sides of the boom 18 with each of their inner bevel pinions 28 in mesh with the inner bevels of the double bevel gears 29.

The double bevel gears 29 are freely mounted on the boom shaft 19 and may be spaced between the opposite sides of the boom 18 and the opposite tower bearing members 20 in any desired manner, such as by collars 38. As best shown in Figs. 7 and 8, the gear segments of the gear 29 are formed on the outer race of a concentric ball bearing, the inner race being mounted on the shaft 19. The outer bevels of the double bevel gears 29 are in mesh with the bevel pinions 30, carried by the upright drive shafts 31, so that the drive is transmitted through the gears 29 without affect upon the boom shaft 19, the segments of the gears 29 merely rotating about their supporting ball bearings. Thus it will be seen that when either of the upright shafts 31 is driven, its pinion 30 will drive its associated double bevel gear 29 which in turn will drive its associated radial shaft 27 and thereby drive the wheel 15 to which it is connected. In this manner each of the wheels 15 are separately driven so that they may be separately controlled. Furthermore, the wheel drives are distinct from the boom 18 so that the wheels 15 may each be driven separately with relation to the boom 18.

As each of the wheels 15 are separately driven, so likewise is the boom 18 separately driven so that it may be rotated without relation to the drive of wheels 15. The large bevel gear 35 is fixed to the boom shaft 19 and is in mesh with the bevel pinion which is carried on the upper end of a separate upright drive shaft 37 that is journaled outside of the rear section of the tower 21, whereas the upright wheel drive shafts 31 are journaled inside of their respective tower segments 21. Thus when the upright shaft 37 is driven, its pinion 36 drives the gear 35 which thereby drives the boom shaft 19 to rotate the boom 18 irrespective of the drives for the wheels 15. Even though the inner races of the gears 29 are rotated with the boom shaft 19, their anti-friction bearings will preclude transmission of this rotation to the wheel drives. As indicated in Fig. 2, the upright shafts 31 and 37 are driven at their lower ends by means of worms 45 and 46 respectively, mounted on a horizontal power shaft 47 which is driven through the medium of a worm gear 48 mounted thereon and in mesh with a worm 49 fixed on the shaft 50 of a small electric motor 51. Thus all of the upright shafts are driven by a single source of power.

It is desirable to control each of the upright shafts separately, and therefore means are provided for disengaging their drives at will, as best shown in Fig. 3. The shaft 47 is journaled in bearing members 55 mounted on the base 40, one end of the shaft 47 extending beyond one of the bearing members 55 to terminate with the worm gear 43. Adjacent the worm gear 43, a driving clutch member 56 is fixed on the shaft 47 with its mating driven clutch member 57 mounted between it and the bearing member 55, reference being made to Fig. 9. The driven clutch member 57 includes a sleeve portion 58 on which is mounted the worm 46 for driving the upright shaft 37. A helical spring 59 is compressed between the clutch sleeve 58 and the adjacent bear-

ing member 55 so as to resiliently urge the driven clutch element 57 into engagement with the driving clutch element 56.

When the clutch elements 56 and 57 are in driving relationship, the worm 46 is then driven and drives a worm gear 60 mounted on the upright shaft 37. A yoke portion 61 is provided on the clutch sleeve 58 to cooperate with a yoke 62 on the end of a lever 63 that is centrally mounted on a pivot 64. The other end of the lever 63 is connected to the core 66 of a solenoid 67 by link 65. Thus when the solenoid 67 is energized to withdraw its core 66, the lever 63 is swung on its pivot 64 to swing its yoke 62 against the clutch yoke 61 and thereby disengage the driven clutch member 57 by moving it against the compression of the spring 59. In this manner, the rotation of the boom 18 is controlled through the operation of the solenoid 67. It naturally follows that when the solenoid 67 is de-energized its core 66 is released so that the spring 59 may again urge the driven clutch member 57 into engagement with the mating driving clutch member 56 to again effect the drive of the boom 18.

In view of the fact that the boom 18 is relatively heavy and develops sufficient momentum to continue rotation after the clutch 57 is disengaged, particularly if one or both of the wheels 15 are still driven, it is necessary to provide a braking means therefor. It is more convenient to associate this braking means with the upright drive shaft 37 in the form of a pair of friction blocks 70 (Figs. 3, 9 and 10), although other braking means may be employed. The blocks 70 are positioned on opposite sides of the shaft 37 and of a pin 71 mounted in the base 40; and an adjusting screw 72 extends through the blocks 70 between the shaft 37 and the pin 71. By this arrangement, the braking blocks 70 are held in frictional engagement with the shaft 37 which engagement may be regulated by the screw 72 so as to apply sufficient friction to slow the shaft 37 to a stop when the clutch 57 is disengaged, but not to interfere with the rotation of the shaft 37, when the clutch 57 is in driving engagement.

It has been found that if the worm gear 60 is fixed to the shaft 37 the rotation of the boom 18 will start with a jerk as soon as the clutch 57 is thrown into frictional engagement with the driving clutch 56. In order to provide a smooth start for the boom 18, the worm gear 60 is freely mounted on the upright shaft 37 but is drivingly connected therewith by a one-way clutch in the form of a helical spring 75 loosely coiled around the shaft 37 and having one end 76 fixed to the gear 60, as by screw 77. Thus when the gear 60 is driven by the worm 46, it revolves the end 76 of the spring 75 and thereby tightens the coil of the spring 75 around the shaft 37 so as to grip and rotate it with the gear 60. The gripping or clutching action of the spring 75 is relatively slow, and also there is a small amount of slippage between it and the shaft 37, so that the rotation of the boom 18 is started gradually and without shock to the apparatus.

Due to the difference in weight, and consequently the difference of inertia or momentum of the wheels 15 in comparison to the boom 18, the wheel drive and braking mechanism is considerably less complicated. The lower ends of the upright shafts 31 each have a worm wheel 80 fixed thereon which is adapted to mesh with the worms 45 respectively on the shaft 47. The lower end of each shaft 31 is journaled in one end of a lever 81 that has its other end con-

nected with the core 84 of a solenoid 85 by a link 82 so as to be moved in one direction by said solenoid against the bias of a tension spring 83 also connected to the lever 81. The lever 81 is mounted on a pivot 86 intermediate its ends so that the spring 83 urges the lever 81 about its pivot 86 to swing the gear 80 into meshing engagement with the worm 45 whereas upon energization, the solenoid 85 retracts its core 84 pulling the rod 82 to swing the lever 81 about its pivot 86 and to move the gear 80 out of engagement with the worm 45.

In view of the fact that the shafts 31 are relatively light they may be loosely journaled in, and suspended from, the brackets 41 at their upper ends to accommodate the swinging of their lower ends to engage or disengage their gears 80 with the worms 45. In order to limit the swinging movement of the shafts 31 away from the worms 45, and also to form a stop or brake to prevent further rotation when the worm gears are disengaged, a tooth or wedge member 87 is fixed diametrically opposite each of the worms 45, relative to the gears 80, so as to be engaged by the teeth of the gears 80 when they are swung out of mesh with the worms 45. Thus it will be seen that the springs 83 will normally retain the gears 80 in mesh with the worms 45 to drive the respective wheels 15, but, upon energization, the solenoid 85 retracts the gears 80 from the worms 45 and into engagement with the stops 87 so that the drive for the wheels 15 is not only halted, but further rotation is prevented.

Even though the wheel drive shafts 31 are held stationary by having their worm gears 80 engaged with the stops 87, the rotation of the wheels 15 will not necessarily be halted. If the drive of the boom 18 is continued, then the wheels 15 will be rotated at a speed that is somewhat slower than their normal speed. This is due to the fact that the bevel pinions 30 mounted on the shafts 31 are not withdrawn from their respective double bevel gears 29 and therefore hold these gears stationary. The bevel pinions 30 are barely moved when the shafts 31 are swung to braking position because said shafts are fulcrumed in the upper supporting brackets 41 and the bevel pinions 30, being positioned immediately adjacent the brackets 41, are subject to a very small movement. As these bevel pinions are not moved sufficiently to disengage them from their respective double bevel gears 29, the gears 29 will be locked with their respective shafts 31 when said shafts are held stationary by the stops 87. If the rotation of the boom 18 is continued when the double bevel gears 29 are held stationary, the radial shafts 27 will be revolved with the boom 18 and rotated by their bevel pinions 28 as said pinions travel around their respective double bevel gears 29. Of course, if the shafts 27 are rotated, then the wheels 15 will be rotated.

It naturally follows that the speed of this rotation will be somewhat less than the normal driving speed. It will be understood that either one of the wheels may be controlled in this manner while the other is driven at normal speed. It will therefore be seen that either or both of the wheels 15 may be driven at a normal rate of speed, either while the boom is driven or held stationary, or that either or both of the wheels 15 may be driven at a slower speed while the boom is driven, or the wheels 15 and the boom 18 may all be held stationary. Of course, by changing the relative position of the fulcrums

for the shafts 31, the pinions 30 could be disengaged from the gears 29 and thereby stop driving rotation of the wheels 15, as the gears 29 would be rotated with the boom shaft 19, due to friction, and there would be no relative movement between gears 29 and the pinions 28. According to the present disclosure, the arrangement is such that the wheels and the boom are normally in driving engagement and may have their drives disconnected only by the positive operation of a suitable disconnecting or braking means. This arrangement is preferred because the device may be completely disconnected, as by a master switch, when it is not in use. It is obvious, however, that the arrangement could be reversed, with the rotatable elements normally out of driving connection but positively engaged by suitable control mechanism.

In machines of lighter construction, a modified arrangement may be employed for driving the boom 18 and wheels 15. This arrangement is more economical in design due to its simplicity of construction. The basic principle of this modification comprises the swingable mounting of all three of the upright drive shafts and the use of beveled gears rather than worms and worm gears. This arrangement permits the positioning of the three upright shafts in line directly above the horizontal drive shaft which may be parallel to the axis of the boom 18. This modified structure is shown in Figs. 12 and 13, wherein the horizontal drive shaft 47 is positioned centrally between the legs of the tower 21 and has fast thereon two bevel gears 45' and one bevel gear 46'. The two bevel gears 45' are mounted in opposed relation to each other so as to drive said shafts 31a, respectively, in opposite directions to each other and thereby drive the wheels 15 in the same direction. These two upright wheel drive shafts 31 and the upright boom drive shaft 37 are mounted immediately above the horizontal drive shaft 47 and have fast on their lower ends, respectively, bevel gears 80' and 60', to mesh with the bevel gears 45' and 46'.

A lever 81' is connected at one end with each of the upright wheel drive shafts 31, is pivotally mounted on a stud 86, and is connected at its opposite ends between a spring 83 and the armature 84 of a solenoid 85. The spring 83 tends to pull the lever to engage each bevel gear 80' with its bevel gear 45' whereas the solenoid operates to disengage these bevel gears. It has been found that no brake member is necessary for the wheel drive shafts in view of the fact that rotational friction is greater than the momentum created by the lightweight structure. A similar arrangement is provided for the upright boom drive shaft 37 which is connected with a lever 63' that is pivotally mounted on a stud 64 and connected with a spring 59' and a rod 65 of the armature 66 of the solenoid 67. It has been found that it is preferable to provide a brake means for the boom drive shaft 37 because, regardless of its weight, the continued rotation of one of the wheels 15 tends to cause continued rotation of the boom 18. Consequently, a brake member 70', such as a toothed member, is positioned so as to be engaged by the bevel gear 60' when the latter is disengaged from the gear 46' on the power shaft 47.

In order to enhance the appearance and increase the attractiveness of the apparatus, it is desirable to position small electric lights on the movable parts of the apparatus so as to define, in lines of light, the movement of the parts when

the device is in operation. For instance, as best shown in Fig. 2, electric lamps 90 may be mounted in sockets 91 which are supported by the cross braces 92 of the wheels 15. The lamps 90 are of the small variety which may be operated on a current of 12 volts or less and, consequently, in order to simplify construction, they may be grounded by their sockets 91 directly to the cross braces 92 of the apparatus in view of the fact that the voltage is so small as to be harmless. Accordingly, but a single line is required to supply current to the lamps 90 as the return circuit is effected through the apparatus.

As best shown in Fig. 8, a single supply line 93 may be run up one of the structural members of the tower 21 and connected by a screw 94 to a spring finger contact 95 that bears on a button contact 96 mounted axially on the end of the boom shaft 19. The boom shaft 19 is tubular so that a line 97, which is connected with the contact 96, may extend through the center thereof to connect with branch wires 98 which extend out through openings 99 in the shaft walls and along the opposite sides of the boom 18 to the opposite ends thereof. A spring finger contact 100 is mounted at each end of the boom and on opposite sides thereof and is connected as by screws 101 with its respective branch line 98. This structure is shown in enlargement in Fig. 11. Each of these spring finger contacts 100 bear against button contacts 102 mounted axially on the ends of the wheel shafts 16. The wheel shafts are likewise tubular to accommodate a wire 103 which is in electrical connection with the button contact 102 and is connected to a plurality of radially extending branch lines 104 which are run out the spokes of the wheel 15 and across the braces 92 to the sockets 91. Obviously, the entire circuit is properly insulated from the apparatus, with the exception of the lamps that are grounded to the apparatus. The spring finger and button contacts provide a simplified, economical, but highly efficient, means for transferring current between relatively movable members and thereby avoid the use of the more complicated and expensive brush and collector ring structure. This spring finger and button contact system is highly efficient in the present instance due to the fact that only one circuit is being transferred, there being no return circuit, as such, due to the fact that the lamps are grounded directly to the apparatus. It will be understood that lamps may be mounted on any suitable part of the apparatus but the arrangement shown provides two circles of light, which circles move through a circular path, and it is believed that this arrangement is the most desirable.

The device is so arranged that it may be controlled remotely, and, accordingly, a series of posts, or contacts, are mounted on the base and they may be connected to suitable control members and to a suitable source of current supply. For instance, as shown in Fig. 3, a series of posts are mounted on an insulating plate 110 which is fixed on the base 52. One post M is connected by line 111 to the motor 51. The next post S is connected by line 112 to one of the solenoids 85. The next post S' is connected by line 113 to the solenoid 67. Another post S'' may be connected by line 114 to the other solenoid 85. Another post L, for supplying current to the lights 90, may be connected by the line 115 with the conductor 93 which extends up one of the structural members of the tower 21.

As hereinbefore set forth, the lamps 90 are grounded through the apparatus to the base 52. This same system is employed for all of the electric apparatus in view of the fact that all of it is adapted to operate at a harmless current of 12 volts or less and, accordingly, the motor 51, solenoid 67 and the solenoids 85 are each grounded to the base 52 so that the return circuit for each of these elements is made through the base.

Accordingly, a post G is connected by a line 116 with the base 52. It will be understood that lines will run from each of the individual posts and from the common ground post G to the control member and source of supply for each of the electrical elements. That is, lines will run from posts G and L to a suitable switch and current source to control the operation of the lights 90. Similarly lines will run from the posts G and S' to a suitable switch and current source to control the respective solenoid 85.

A modification of the apparatus is shown in Figs. 14, 15 and 16. This structure comprises the usual single wheeled type of Ferris wheel and includes a wheel 120 that pivotally supports passenger carriers 121 at spaced points about its periphery, and is fixed on a tubular shaft 122 that is journaled in spaced bearing plates 123 supported by spaced tower elements 124 that are mounted on a base 125. A bevel gear 126 is fixed on the tubular shaft 122 and meshes with a bevel pinion 127 carried by a vertical shaft 128 that also has fixed thereon, a worm gear 129 that is in mesh with a worm 130 fixed on the shaft 132 of a motor 133. Lights 134 are seated in sockets 135 that are supported by, and grounded to, cross braces 136 of the wheel 120.

Both the lights and the motor are grounded through the apparatus to a ground terminal G, a supply terminal M being connected by a wire 137 to the motor 133 and a supply terminal L being connected by wire 138 that extends along the base and up the tower 124 to be connected with a spring finger contact 139 mounted on the outer bearing plate 123. The spring contact 139 bears against a button contact 140 mounted in the end of the tubular shaft 122 and connected to a line 141 extending through part of said shaft 122 and branching radially in lines 142 which extend along the spokes of the wheel 120 and across the braces 136 to the lamp sockets 135.

The advantage of this structure resides principally in its simplicity of arrangement and economy of parts. For instance, but a single drive shaft 128 extends between the motor 133 and the wheel shaft 122, the drive shaft 128 being connected directly to the motor drive by its worm gear 129. Simplicity of wiring or current supply is also a feature in that a single line extends to the lights, thereby enabling the use of the simple rotary contact employing but a single spring finger that bears axially on a pivotally mounted button. It will be understood that wires will extend from the ground G and from each of the terminals M and L to respective control devices and current supply, whereby the apparatus may be remotely controlled in its operation.

Although certain specific embodiments of the invention are shown and described, it is obvious that many modifications thereof are possible. The invention, therefore, is not to be restricted except insofar as is necessitated by the prior art and by the spirit of the appended claims.

That which is claimed as new is:

1. An amusement device comprising a stand and, a supporting element mounted on said

11

standard for rotatable movement about a horizontal axis, a plurality of supporting members mounted on said supporting element for rotatable movement about horizontal axes, each having carriers pivotally mounted thereon, a motor, drive means connecting said motor with said supporting element and each of said supporting members to cause them to rotate about their axes, and means for separately disconnecting the drive means for said element and for each of said members.

2. An amusement device comprising a standard, a supporting element mounted on said standard for rotatable movement about a horizontal axis, a plurality of supporting members mounted on said supporting element for rotatable movement about horizontal axes, each having carriers pivotally mounted thereon, a motor, drive means connecting said motor with said supporting element and each of said supporting members to cause them to rotate about their axes, and electromagnetic means for separately disconnecting the drive means for said element and for each of said members.

3. An amusement device comprising a standard, a supporting element mounted on said standard for rotatable movement about a horizontal axis, a plurality of supporting members mounted on said supporting element for rotatable movement about horizontal axes, each having carriers pivotally mounted thereon, a motor, drive means connecting said motor with said supporting element and each of said supporting members to cause them to rotate about their axes, means for separately disconnecting the drive means for said element and for each of said members, and brake means for preventing free rotation of said element and of said members when their respective drives are disconnected.

4. An amusement device comprising a standard, a supporting element mounted on said standard for rotatable movement about a horizontal axis, a plurality of supporting members mounted on said supporting element for rotatable movement about horizontal axes, each having carriers pivotally mounted thereon, a motor, drive means connecting said motor with said supporting element and each of said supporting members to cause them to rotate about their axes, means for separately disconnecting the drive means for said element and for each of said members, and brake means cooperative with the drive means for said rotatable element and for each of said rotatable members for preventing free rotation of said element and of said members when their respective drives are disconnected.

5. An amusement device comprising a standard, a supporting element mounted on said standard for rotatable movement about a horizontal axis, a plurality of supporting members mounted on said supporting element for rotatable movement about horizontal axes, each having carriers pivotally mounted thereon, a motor, drive means connecting said motor with said supporting element and each of said supporting members to cause them to rotate about their axes, electromagnetic means for separately disconnecting the drive means for said element and for each of said members, and brake means cooperative with the drive means for said rotatable element and for each of said rotatable parts for preventing free rotation of said element and of said members when their respective drives are disconnected.

12

6. An amusement device comprising an upright standard, a supporting element mounted on the upper end of said standard for rotatable movement about a horizontal axis, a plurality of supporting members mounted adjacent the edges of said supporting element for rotatable movement about horizontal axes, each of said supporting members having carriers pivotally mounted thereon, a motor, a power shaft driven by said motor, drive means for rotatively driving said supporting element and each of said supporting members to cause them to rotate about their axes and including upright shafts adjacent said standard and connected with said power shaft, and means for selectively disconnecting the drive of said upright shafts from that of said power shaft.

7. Amusement device comprising an upright standard, a supporting element mounted on the upper end of said standard for rotatable movement about a horizontal axis, a plurality of supporting members mounted adjacent the edges of said supporting element for rotatable movement about horizontal axes, each of said supporting members having carriers pivotally mounted thereon, a motor, a power shaft driven by said motor, drive means for rotatively driving said supporting element and each of said supporting members to cause them to rotate about their axes and including upright shafts adjacent said standard and connected with said power shaft, means for selectively disconnecting the drive of said upright shafts from that of said power shaft, and brake means cooperative with the upright shafts for preventing free rotation of said element or of any of said members when their respective drive is disconnected.

8. An amusement device comprising an upright standard, a supporting element mounted on the upper end of said standard for rotatable movement about a horizontal axis, a plurality of supporting members mounted adjacent the edges of said supporting elements for rotatable movement about horizontal axes, each of said supporting members having carriers pivotally mounted thereon, a motor, a power shaft driven by said motor, drive means for rotatively driving said supporting element and each of said supporting members to cause them to rotate about their axes and including upright shafts adjacent said standard and connected with said power shaft, one of said upright shafts being pendulously journaled adjacent its upper end and carrying means at its lower end for engagement with and to be driven by said power shaft, and means for separately disconnecting the drive of said upright shafts from that of said power shaft and including means for swinging said pendulous shaft away from said power shaft.

60 9. An amusement device comprising an upright standard, a supporting element mounted on the upper end of said standard for rotatable movement about a horizontal axis, a plurality of supporting members mounted adjacent the edges of said supporting element for rotatable movement about horizontal axes, each of said supporting members having carriers pivotally mounted thereon, a motor, a power shaft driven by said motor, drive means for rotatively driving said supporting element and each of said supporting members to cause them to rotate about their axes and including upright shafts adjacent said standard and connected with said power shaft, one of said upright shafts being pendulously journaled adjacent its upper end and carrying means at its

65 70 75

lower end for engagement with and to be driven by said power shaft, means for separately disconnecting the drive of said upright shafts from that of said power shaft and including means for swinging said pendulous shaft away from said power shaft, and brake means cooperative with the upright driven shafts for preventing free rotation of said element or of either of said members when their respective drives are disconnected and including a stop positioned for engagement by said engaging means when said pendulous shaft is swung away from said power shaft.

10. An amusement device comprising an upright standard, a supporting element mounted on the upper ends of said standard for rotatable movement about a horizontal axis, a plurality of supporting members mounted adjacent the edges of said supporting element for rotatable movement about horizontal axes, each of said supporting members having carriers pivotally mounted thereon, a motor, a power shaft driven by said motor, a clutch including a driving member fixed on said shaft and a driven member normally engaging said driving member, driving means for rotatively driving said supporting element and each of said supporting members to cause them to rotate about their axes and including upright shafts adjacent said standard and connected with said power shaft, one of said upright shafts having a driving engagement with said driven clutch member, and means for separately disconnecting the drive of said upright shafts from that of said power shaft and including means for disengaging said clutch members.

11. An amusement device comprising an upright standard, a supporting element mounted on the upper ends of said standard for rotatable movement about a horizontal axis, a plurality of supporting members mounted adjacent the edges of said supporting element for rotatable movement about horizontal axes, each of said supporting members having carriers pivotally mounted thereon, a motor, a power shaft driven by said motor, a clutch including a driving member fixed on said shaft and a driven member normally engaging said driving member, driving means for rotatively driving said supporting element and each of said supporting members to cause them to rotate about their axes and including upright shafts adjacent said standard and connected with said power shaft, one of said upright shafts having a driving engagement with said driven clutch member, means for separately disconnecting the drive of said upright shafts from that of said power shaft and including means for disengaging said clutch members, brake means cooperative with the upright shafts for preventing free rotation of any of said members when their respective drives are disconnected, and brake means for said clutch driven upright shaft comprising a friction brake which is constantly in frictional engagement with said shaft.

12. An amusement device comprising an upright standard, a supporting element mounted on the upper ends of said standard for rotatable movement about a horizontal axis, a plurality of supporting members mounted adjacent the edges of said supporting element for rotatable movement about horizontal axes, each of said supporting members having carriers pivotally mounted thereon, a motor, a power shaft driven by said motor, a clutch including a driving member fixed on said shaft and a driven member normally engaging said driving member, driving

means for rotatively driving said supporting element and each of said supporting members to cause them to rotate about their axes and including upright shafts adjacent said standard and connected with said power shaft, the upright shaft included in the drive for said supporting element having means freely mounted thereon and in driving engagement with said driven clutch member, a delayed action clutch means drivingly connecting said upright shaft and said loosely mounted means, and means for separately disconnecting the drive of said upright shafts from that of said power shaft and including means for disengaging said clutch members.

13. An amusement device comprising an upright standard, a supporting element mounted on the upper ends of said standard for rotatable movement about a horizontal axis, a plurality of supporting members mounted adjacent the edges of said supporting element for rotatable movement about horizontal axes, each of said supporting members having carriers pivotally mounted thereon, a motor, a power shaft driven by said motor, a clutch including a driving member fixed on said shaft and a driven member normally engaging said driving member, driving means for rotatively driving said supporting element and each of said supporting members to cause them to rotate about their axes and including upright shafts adjacent said standard and connected with said power shaft, the upright shaft included in the drive for said supporting element having means freely mounted thereon and in driving engagement with said driven clutch member, a delayed action clutch means drivingly connecting said upright shaft and said freely mounted means, means for separately disconnecting the drive of said upright shafts from that of said power shaft and including means for disengaging said clutch members, brake means cooperative with the upright shafts for preventing free rotation of any of said members when their respective drives are disconnected, and brake means for said element driving upright shaft comprising a friction brake which is constantly in frictional engagement with said shaft.

14. An amusement device comprising an upright standard, a horizontal shaft journaled in the upper end of said standard, a supporting element mounted on said horizontal shaft for rotatable movement therewith, a plurality of supporting members mounted adjacent the edges of said supporting element for rotatable movement about horizontal axes, each of said supporting members having carriers pivotally mounted thereon, a motor, a plurality of drive transfer means freely mounted on said horizontal shaft, one for each supporting member, a plurality of radially disposed shafts carried by said supporting element, each drivingly connecting one of said transfer means and one of said supporting members, and a plurality of upright shafts adjacent said standard and drivingly connected with said motor, one of said upright shafts having a driving connection with said horizontal shaft to drive said supporting element and each of the other upright shafts having a driving connection with one of said transfer means to drive its respective supporting member.

15. An amusement device comprising an upright standard, a supporting element mounted on the upper end of said standard for rotatable movement about a horizontal axis, a plurality of supporting members mounted adjacent the edges of said supporting element for rotatable move-

ment about horizontal axes, each of said supporting members having carriers pivotally mounted thereon, a motor, a power shaft driven by said motor, drive means for rotatively driving said supporting element and each of said supporting members to cause them to rotate about their axes and including upright shafts adjacent said standard and connected with said power shaft, said upright shafts being pendulously adjacent their upper ends and carrying means at their lower ends for engagement with connecting means on said power shaft, and means for separately disconnecting the drive of said upright shafts from that of said power shaft and including means for swinging said pendulous shafts away from said power shaft connecting means.

16. An amusement device comprising an upright standard, a supporting element mounted on the upper end of said standard for rotatable movement about a horizontal axis, a plurality of supporting members mounted adjacent the edges of said supporting element for rotatable movement about horizontal axes, each of said supporting members having carriers pivotally mounted thereon, a motor, a power shaft driven by said motor, drive means for rotatively driving said supporting element and each of said supporting

members to cause them to rotate about their axes and including upright shafts adjacent said standard and connected with said power shaft, said upright shafts being pendulously journaled adjacent their upper ends and carrying means at their lower ends for engagement with connecting means on said power shaft, means for separately disconnecting the drive of said upright shafts from that of said power shaft and including means for swinging said pendulous shafts away from said power shaft connecting means, and brake means cooperative with the connecting means on the upright shaft for driving said supporting element for preventing free rotation of said element when its drive is disconnected.
